Machines Corporation, New York, N. Y., a cor-
poration of New York

Application July 1, 1927, Serial No. 202,805
In Germany April 7, 1927

7 Claims. (Cl. 235—92)

This invention relates to accounting or tabulating machines which are controlled by tabulator record cards or sheets for effecting the sorting of the records into groups, the accumulating of the items on the records, the listing of the items, the printing of the totals of the items, or other related accounting operations. The control of the operations of accounting or tabulating machines has, previous to this invention, been effected by means of index points in the form of perforations. The perforations were positioned variously in a record field according to the data interpreted. It was also necessary to represent a character, in most known code systems by a plurality of perforations, arranged in separate adjacent columns, thus resulting in increasing the minimum width of a record sheet. The employment of a code, required a skilled operator to read and transpose from the written data into variously positioned perforations on the record. The transposition of the written data to the record required a special punching operation. The index points in the form of perforations were sensed by an analyzing means, usually a pair of contacts which were made through the perforations. The analyzing means then set up the sorting accumulating or printing mechanisms in accordance with the analysis.

The object of this invention is to control the accounting of tabulating machines by index points on the records other than in the form of perforations for example, by means of printed characters. The invention includes the provision of an analyzing device which may be controlled by the form of the index point, its shape, size, or other physical characteristics. The analyzing mechanism may operate by means of radiant energy, regulated by the index point or character on the record. The radiant energy may take the form of light for energizing sensitive cells. The object of this invention is, further, to analyze the index points or characters by means out of contact with the record during analysis. It is also an object of this invention to cause differential operation of the accounting mechanisms not by means of variously positioning the index points in the record field but by varying the form of the index points. The latter may be located in the same position on the record to differentially control the operation of the accounting mechanisms, its position in the record field being immaterial. The analyzing means, according to this invention, sets up circuits, varied ac-

cording to the analysis, for operating the accounting mechanisms.

Other objects of this invention will be disclosed and pointed out in the succeeding portions of the specification.

In the drawings;

Fig. 1 shows the characters 0-9 positioned in the standard record fields with a showing beneath each character of its resulting representation in a four point code.

Fig. 2 shows the code points in a standard field.

Fig. 3 is a table showing the combination of points corresponding to each character.

Fig. 4 shows the optical analyzing device.

Fig. 5 is a top view of the photocells unit of the device shown in Fig. 4.

Fig. 6 is a schematic showing of a sorting machine using the optical analyzing device.

Fig. 7 shows the optical analyzer applied to a tabulating machine.

Fig. 8 is a detail of Fig. 7 showing the parts when digit 4 is under the analyzing light.

Fig. 9 is a detail of Fig. 7.

Fig. 10 is a modification of the device shown in Fig. 7.

Fig. 11 shows an alternate system of causing variations in the analyzing light by the form of the printed characters.

Fig. 12 is a graph showing the proportion of the field covered by each character and the resulting current.

Fig. 13 is a schematic showing of a form of sorter used with the characters of Fig. 11.

Fig. 14 is a detail of the analyzers used in Fig. 13.

Fig. 15 is a detail of Fig. 13.

Fig. 16 is a schematic showing of a tabulator for records using the character system of Fig. 11.

Referring to Figs. 1, 2 and 3, the record card or sheet has a number of equal portions or fields

20a, in each of which is printed, in accordance with the statistics to be tabulated, one of the digits 0-9 in heavy black type. If four imaginary points be arranged in each field as A, B, C, and D, (see Fig. 2) then each digit when printed in

45 the field will cover one or more of the points, depending on the contour of the digit. For example, character 0 will cover points A and D, leaving B and C exposed (as shown by the unprinted field below the printed digits where the black

50 points are those covered and the white points those exposed); digit 1 will cover points B and C, leaving A and D uncovered; digit 2 will cover points A and C, leaving B and D uncovered; etc.

55 Each digit will cover and uncover a different com-

bination of points thus providing a different code for each character as tabulated in Fig. 3. Now if a single record field 20 be exposed as in Fig. 4 to a beam of light, hereinafter termed the analyzing beam, directed at an angle from the source 21 through a lens 22, the rays of light will be reflected by the exposed or white surfaces of the record field and be absorbed by the black surfaces or digit printed on the field. The reflected rays will pass through a lens 23 which will direct them on a transparent plate 24 such as plate glass, thus reproducing on said plate an image of the record field. Below the plate, in a frame 25 are arranged four light sensitive cells 26, such as potassium cells, in the same order and position relative to the reflected field 27 as imaginary points A, B, C and D in the actual record field. Since the reflected field is dark in portions corresponding to the character on the actual record field, those cells which are directly under the dark portions will not be energized as represented by the black points of Fig. 1. For example, if digit 0 be reflected on field 27, cells 26A and 26D will not be energized while cells 26B and 26C will be exposed to the beam of reflected light and be energized. It is, of course, understood that the form of the digit may be varied, that the number of cells may also be varied both in number and arrangement or either; that, instead of digits, letters or other characters may be used; and that in each case, the printed character may be so shaped as to cover a different combination of basic points, thus giving a distinctive characteristic to each character.

One adaptation of this method of energizing light sensitive cells in combinations selected by a printed digit on a record card or sheet is in connection with a record sorting machine shown in Fig. 6. The picker blade 28, of any well known type, feeds one record card at a time from a magazine 29 to an analyzing station 30 where one field of the card is held exposed to the analyzing beam which reflects the digit occurring on the field onto the plate 24, resulting in energizing the cells in frame 25 according to the code of Fig. 3. When the reflected light strikes the photo cell, a current is produced in the cell which is amplified in a well known manner by amplifying unit 31 connected to each cell consisting preferably of vacuum tubes. The amplified current from each cell energizes a magnet 32 to cause it to attract its armature 33 which, by a connecting link 34, swings one of the deflectors 35 of the sorter to open position. To time the action of the magnets, a cam 36 moving in synchronism with the picker 28 closes contacts 37 at the proper time to complete the circuit from the photo cells through the magnets. Until the card has reached its proper pocket 38, the deflectors are held open by a detent 39 rigid with an armature 40, thus holding each armature 33 in its actuated position. At the end of the machine cycle, the circuit through all the magnets 32 is completed by a cam 42 closing contacts 43, thereby attracting armatures 40 causing the detents 39 to release the armatures 33 which return to their normal position. It will be understood that the combination of deflectors opened depends on the combination of energized cells, which in turn is selected by the digit on the field which is being then analyzed.

The adaptation of the invention to one form of a tabulating machine is shown in Figs. 7, 8 and 9. As is usual in tabulating machines, for each record column, or in this case record field,

there is provided an individual analyzing, accumulating and printing means. For the purpose of simplifying the explanation, only one such unit is illustrated and described. Thus Fig. 7 shows the mechanism operating to analyze, accumulate and print in accordance with the digit contained in one standard record field 20. The analyzing beam energizes cells 26 in accordance with the character code hitherto explained and the resulting current is amplified by units 31 to energize translating magnets 32, at a period in the cycle determined by cam 36 closing contacts 37, as in the previous machine. In this case, the magnets 32 serve to control the differential mechanism which actuates the accumulator and printer in accordance with the analyzed digit. Magnets 32, upon energization thereof in accordance with the code, attract armatures 44 linked with contact fingers 45 by means of rods 46. After actuation, the armatures are retained in position by detents 47 which are moved to release the armatures at the end of the cycle, by a bar 48 having lugs 49 contacting the detents. Bar 48 is actuated by armature 50 attracted by magnet 51 when contacts 52 are closed at the end of the cycle by a cam 53. A commutator 54 is provided with ten conducting segments 55, corresponding in succession to the digits 0 to 9. Rotating in synchronism with the movement of type bar 56 is a pair of diametrically opposed brushes 57, 57'. In the rotation of the brushes, contact will first be made with the segment corresponding to digit 0 then with the segment corresponding to digit 1, etc. Fig. 8 illustrates the position of the contact fingers 45 when digit 4 is analyzed. The code for digit 4 (see Fig. 3) results in energizing cells 26A and 26B, causing magnet 31A to move the contact finger 45A to close contacts 58A and magnet 31B to close contacts 58B. When the brush 57 reaches the commutator segment 55 corresponding to digit 4, a circuit is completed from power source line 60 through cam closed contacts 61, contacts 58A, 58B, the fifth commutator segment 55, the brush 57, brush 57', line 62, magnet 63 and back to the other line 64 of the power source. This circuit results in energizing magnet 63 causing it to attract its armature 65 as more fully shown in Patent 1,780,685 to release a toothed detent member 66 for engagement with a toothed portion 67 of type bar 56 moving in synchronism with the rotation of the commutator brush 57. When stopped by the toothed member, the type bar has a type lug 68 (Fig. 9) corresponding to digit 4 in printing position. At the beginning of the rising movement of the type bar, an accumulator wheel 70 is demeshed from a rack 71 on the type bar in a manner fully shown in said Patent No. 1,780,685. Upon descent of the type bar after printing, the wheel is thrown into mesh with rack 71 to cause it to rotate four steps. For a more complete and detailed explanation of the aforesaid accumulating and printing mechanism shown in Fig. 9, reference may be had to said Patent No. 1,780,685, dated November 4, 1930 and assigned to the assignee of the instant case.

In Fig. 10 is shown a modified form of tabulator control which differs from the previous form in that the control magnets connected to the light responsive cells are dispensed with. In this form a constantly rotating semi-conductor, such as an agate roll 72 for example, having a high contact resistance, as is well known, is associated with a plurality of metal strips 73 one end of each of which is connected to a spring 74 to hold the

strip in sliding engagement with the roll 12. The tension of the spring is such that the friction between the roll and strip is not sufficient to cause movement of the strip in response to the rotation of the roll. In other words, the roll normally rotates freely without affecting the strip. Each strip is connected to one terminal of one of the light responsive cells 26 and the roll is connected to one terminal of a power source S the other terminal of which is connected to the free terminals of the cells. A pair of cam-controlled contacts 15 is provided in series with the power source to prevent energization of the circuits except at such times as the records are in analyzing position, as is usual in these machines. When any of the cells 26 are energized in response to light rays, circuits are established extending from the roll through the cells in question to the strips connected therewith and the resulting condenser action between the roll and strips causes an electrostatic attraction between them, whereupon the strips are held firmly to the roll and move with it. The movement of a strip shifts the associated switch member or members 45 in accordance with the particular digit on the controlling record field to differentially interrupt the upward movement of the corresponding type bar, as in the previous modification, shown in Fig. 7. The relay 12, 13 being operated by a very low current, there is a possibility that even a photo cell in the dark portion of the field may have sufficient minimum current to actuate the relay. To counterbalance the force of this minimum current, springs 16 are provided to hold down the links actuating the switches 45.

In Fig. 11 is shown a system of printing characters on a standard field 20a which does away with the necessity of analyzing the field at predetermined basic points. The characters are differentiated from each other by varying their relative sizes, each character covering a different percentage of a standard field. If characters 0-9 for example be printed on the fields 20a, they may be varied in area according to the percentages marked in Fig. 11. If the analyzing beam of light be directed with uniform intensity at all portions of the field, the quantity of light reflected toward the photo cell unit will be varied according to the area of the field covered by the character. In this system, only one photo cell is required for each analyzing mechanism, which cell will have a current produced therein varying with the quantity of light reflected and consequently with the size of the character. Each character thus produces a different current in the photo cell as illustrated by the dotted line in Fig. 12 which also shows the graph of the area covered by the characters of Fig. 11, the intensity of the current varying inversely as the area of the character which constitutes the black portion of the field.

In Fig. 13 is shown an adaptation of this system to a sorter for record cards. The rotating picker device 11 feeds one card at a time from magazine 18 to a series of feed rollers 19 which conduct the card beneath a series of photo cells 80, one for each sorting pocket 81. The card field is illuminated diagonally at each sorting station by an individual light source 82 (Fig. 14). The rays of light reflected from the field are concentrated by means of a converging lens 83 on the transparent plate 84 above which is the photo cell 80. The current in the photo cell energizes a magnet 85 corresponding thereto to attract its armature 86 and raises deflector 87 to intercept the advanc-

ing card, causing it to drop into the pocket 81. As in Fig. 16, the magnet coil 85 for each pocket has a different number of ampere turns, the minimum number of turns being on the magnet in the reject pocket, taking care of blank fields, the next higher number of turns on the magnet in the 1 pocket and the greatest number of turns on the magnet in the 9 pocket. In Fig. 13 the 9 pocket is omitted for lack of space. The card passes successively through the reject sorting station 10, the 0 sorting station, the 1 sorting station, the 2 sorting station, etc., in the order indicated. It is known that the magnetic attraction of a coil varies directly as the number of ampere turns. If, for example, digit 5 is on the card field, it will pass successively under the analyzing cells for the reject 0, 1, 2, 3 and 4 pockets. The current produced in any of these cells energizes the magnets for these pockets but the magnetic field set up by the coils of these magnets is insufficient to attract their armatures. When the card reaches the 5 analyzing cell, the number of ampere turns of the magnet in the 5 pocket is sufficient to attract the 5 armature and hence guide the card into the 5 pocket. To hold the armature in position till the end of the cycle, after actuation, a detent 88 is provided, behind which the armature 86 snaps as soon as it is attracted. At the end of the cycle, a magnet 89 under control of cam 90 closing contacts 91, actuates detent 88 to release the armature 86. The current through the cells and the magnets is completed when the cards are in their proper position in front of the photo cells, by means of contacts closed by cam 92.

In Fig. 16 is shown a tabulating machine built for the system of character differentiation illustrated in Fig. 11. The analyzing device used in this machine contains only one photo electric cell which is controlled by the analyzing light 40 from a source 21. The light passes through lens 22 and falls upon the field 20a having the character printed thereon, the image of the card field being concentrated onto the transparent plate 93, behind which is the photo cell 94 energized 45 in proportion to the quantity of light cast on the plate. The photo cell current is then amplified by the amplifier unit 95 and flows through 10 magnet coils 95' in series, each magnet coil having a different number of turns, graduated to 50 correspond to the size of the black portion of the character field. Upon passage of a card field through the analyzing beam, a current is produced in the photo cell which varies in intensity inversely as the black area of the character, the 55 strongest current thus produced being for digit 0 and the smallest for digit 9 (see the graph, Fig. 12). For each current flow through the series of magnet coils, that coil which corresponds to the digit in the illuminated position and those 60 coils corresponding to the digits larger than the one in said position, will be sufficiently energized to attract their armatures 96'. Thus upon the passage of digit 0 through the illuminating field, the maximum intensity of current will be produced which is sufficient to energize all the magnet coils to attract their armatures. Upon the passage of a 4 digit, the current produced is not sufficient to make effective the magnets corresponding to digits 0, 1, 2 and 3, but does make 70 effective magnets corresponding to 4 to 9, inclusive. The attraction of an armature 96' results in its actuating one of a series of detent bars 97-0 to 97-9 inclusive to engage a toothed segment 98, moving with which is the series of 75

type lugs 88. An accumulator wheel 100 is rotated by the teeth 101 of the segment 88. Upon the passage of a 0 digit, as explained, all the armatures will be actuated; consequently all the 5 detents 97 will be actuated and, as a result, oscillation of the segment is completely prevented, a lug 102 being engaged by the detent 97—0 corresponding to the 0. When a digit higher than 0 is analyzed, the segment will oscillate until 10 lug 102 contacts the detent corresponding to the analyzed digit, which is the first of all the raised detents. By means not necessary to an understanding of this invention, the hammer 103 is actuated to strike the type lugs 88, when the 15 segment comes to rest, and print on the paper 104. The segment is provided with means (not shown) to cause it to move as soon as the detent bars 97 have been actuated, and the accumulator wheel is disengaged (by means not shown) from the drive of the teeth 101, upon the return stroke 20 of the segment. It is, of course, understood that as many mechanisms, like that shown in Fig. 16 are provided, as there are columns on the record card or sheet.

25 It is apparent that in the above described machines, means are provided to prevent light not reflected by the card field from reaching the photo cells.

30 It is understood that the invention may be carried out in a great number of ways and by a variety of means.

The record card per se forms the subject matter of my copending application, Serial No. 202,806, filed July 1, 1927.

35 What is claimed is:

1. An analyzing device for controlling statistical mechanism from records bearing character designations, said device comprising a single light 40 sensitive element, means including a source of light for examining a character designating field on the records and cooperating with the records to subject the single light sensitive element to different amounts of light according to designations of different characters on the record field, 45 and selective means controlled by the light sensitive element according to the different amounts of light to which it is subjected.

2. An analyzing device for controlling statistical mechanism from records bearing visually

readable characters, each distinct character covering a different proportion of a delimited area, comprising a single light sensitive element, means including a source of light for examining the delimited character bearing area on the records and cooperating with the delimited area on the records to subject the single light sensitive element to different amounts of light according to the proportion of the area covered by the characters represented thereon, and selective means controlled by the light sensitive element according to the different amounts of light to which it is subjected. 10

3. In an accounting machine having a plurality of movable elements adapted to be differentially set, a plurality of electromagnets adapted to control the setting of said elements, said magnets being connected in series, and a light sensitive device associated with said magnets for controlling the energization thereof. 15

4. The invention set forth in claim 3 in which the different magnets are designed to be operated by different amounts of current. 20

5. In an accounting machine having a plurality of movable elements adapted to be differentially set, a plurality of electromagnets connected in series for controlling the setting of said elements, the different magnets being designed to be operated by different amounts of current, a light sensitive device associated with said magnets for controlling the amount of current flowing therethrough, and a record having characters thereon for controlling the amount of light falling upon said device, said characters being of progressively different total areas in accordance with their 30 values. 35

6. A process for carrying out calculating and like operations characterized by exploring a record by means of light rays and causing said rays to influence photo-sensitive means upon the 40 record being of predetermined character, and causing such means to control operations of calculating mechanisms.

7. A process for carrying out statistical and like operations characterized by exploring a record bearing statistical indications by means of light and causing the light to radiate as means for selecting certain records. 45

MICHAEL MAUL.
